UNITED STATES PATENT OFFICE.

FRANK D. HOWE, OF AKRON, OHIO, ASSIGNOR, BY MESNE ASSIGNMENTS, TO INTERNATIONAL HARVESTER CORPORATION, A CORPORATION OF NEW JERSEY.

END-GATE.

1,150,195.

Specification of Letters Patent.

Patented Aug. 17, 1915.

Application filed January 9, 1913. Serial No. 740,986.

To all whom it may concern:

Be it known that I, FRANK D. HOWE, a citizen of the United States, residing at Akron, in the county of Summit and State 5 of Ohio, have invented certain new and useful Improvements in End-Gates, of which the following is a full, clear, and exact specification.

My present invention relates to end-gates 10 for vehicles, such as wagons and the like, and more particularly to means for adjustably supporting and locking said end-gates.

The object of this invention is to simplify 15 and improve means for adjustably supporting and locking end-gates of vehicles. This object is accomplished by providing at either side of the vehicle or wagon box adjacent the end-gate, ladder members, the rungs of which are adapted to be engaged 20 by hooks on the end-gate chains or connectors for holding the end-gate in any adjusted position, and members associated with said end-gate chains or connectors for locking said end-gate in its closed position.

25 The invention is illustrated on the accompanying sheets of drawings, in which—

Figure 1 is a fragmentary rear elevation of a wagon box equipped with my invention; and, Fig. 2 is the side elevation of the same.

30 The various novel features will be apparent from the description and drawings and will be particularly set forth in the appended claims.

The vehicle or wagon may have any kind 35 of a box 1, provided with an end-gate 2, pivotally mounted at 3, the end-gate being held in closed position by the usual springs 4 which are secured to the box 1. Various means have been used whereby end-gates 40 are held in different adjusted positions. However, means thus far employed have not fully and satisfactorily met all of the requirements for successful commercial usage. In the arrangement which is here illustrated, 45 ladder members 5 are secured to the back cross member 6 of the wagon box 1, and also secured to the sides of the wagon box 1 adjacent the end-gate. These members 5 are called ladder members because they resemble ladders in that they have rungs 7 at intervals which are adapted to be engaged by 50 hooks 8 at the ends of chains or connectors 9, the other end of each of which is secured to the end-gate by an eye and bolt connection 10. If it is desired to have the end-gate

lie in the same plane with the floor of the wagon box, as illustrated by dotted lines in Fig. 2, the hooks 8 are placed in engagement with the top rungs of the ladder members respectively. If it is desired to slightly 60 raise the end-gate, said hooks are placed into engagement with the rungs just below the top rungs, with the chains passing over the latter. Any number of rungs may be used so that the end-gate may be raised and 65 lowered and fastened in any adjusted position. When the end-gate is raised from the horizontal position, the chains or connectors 9 pass over the top rungs and the hooks brought down on the opposite side of the 70 ladder members, engaging any one of the rungs desired. If it is desired to lower the end-gate from its horizontal position, the hooks 8 are placed into engagement with any of the rungs without passing the chains 75 or connectors over the top rungs. When the end-gate is in closed position, the chains or connectors pass over the top rungs and the hooks are placed into engagement with a stud or projection 11 secured in the end of 80 a pivotally mounted member 12. By means of this pivotally mounted member 12, the end-gate is positively locked in closed position. The end-gate is positively locked depending upon whether or not the chain or 85 connector 9 falls on one side or the other of the pivotal or critical point 13 of the member 12.

As illustrated in Fig. 2, the chain 9 with the end-gate closed is to the left of the pivotal point 13 and the end-gate is locked in closed position. In order to unlock the end-gate, the member 12 is swung counter-clockwise until the chain 9 is shifted to the opposite side of the pivotal point 13, whereupon the hooks 8 can be removed from the studs 11 and the gate lowered any desired degree as hereinbefore set forth. The pivotally mounted member 12 is adapted to engage a stop member 14 to prevent said member, 12, from moving too far in a clockwise direction. It is to be noted that each of the studs or handles 11 of the member 12, has an off-set or eccentric portion 11^a on which a fastening nut 11^b is screwed. By loosening the nut 11^b on either handle 11, said handle may be rotated, as a crank, with the middle of the off-set portion 11^a as a center. This provision is made so that even if the lengths of two chains 9 differ, the handles 11^c

11 can be properly rotated or adjusted so that the tautness of the two chains will be the same when the end-gate is locked in closed position by the member 12. Formed 5 integrally with the ladder members 5, are socket portions 15, into which projections 16 of the side wing members 17 are adapted to fit to hold said side wings in place. Set screws 18 are used for securing the projections 16 in any desired position.

10 The particular ladder member arrangement with its coöperating parts herein disclosed is considered to be the preferred form 15 of my invention. There may be various 15. modifications of the particular arrangement herein illustrated and described, and it is my intention to cover all such arrangements and modifications which do not depart from the spirit and scope of my invention as set 20 forth in the appended claims.

What I claim as new is:

1. In a vehicle, the combination of a vehicle body, an end-gate therefor, ladder members on opposite sides of said vehicle 25 body and adjacent said end-gate, and a connector between said end-gate and ladder members, said connector being adapted to engage various portions of said ladder members to retain said gate in different positions.

2. In a vehicle, the combination of a vehicle body, an end-gate therefor, ladder members on opposite sides of said vehicle body and adjacent said end-gate, a connector 35 between said end-gate and ladder members, said connector being adapted to engage various portions of said ladder members to retain said gate in different positions, and a pivotally mounted member for positively locking said end-gate in one extreme 40 position.

Copies of this patent may be obtained for five cents each, by addressing the "Commissioner of Patents, Washington, D. C."

3. In a vehicle, the combination of a body, a pivotally mounted end-gate, ladder members secured to said body, flexible members secured to said end-gate and having hooks 45 at their ends to engage various portions of said ladder members to support said end-gate in different positions, and a pivotally mounted member on opposite sides of said body to positively lock said end-gate in one 50 position.

4. In a vehicle, the combination of a vehicle body, a gate therefor, a ladder member having rungs and being secured to said body, and a connector secured to said end-gate and having a hook adapted to engage any of the rungs of said ladder member to retain said gate in different positions, said connector passing over the top rung and engaging a different rung when the end-gate is 55 raised from a horizontal position.

5. In a vehicle, the combination of an end-gate, a locking member therefor, a flexible connection between said end-gate and locking member, said locking member having relatively eccentric portions by means of which the tautness of said flexible connection may be varied.

6. In a vehicle, the combination of an end-gate, a locking member therefor including a lever and handle, and a connection between said end-gate and locking member, said handle being adapted to be adjusted relative to said lever to vary the 70 tautness of said connection.

In testimony whereof I affix my signature, in the presence of two witnesses.

FRANK D. HOWE.
